(57) **CLAIM**

The ornamental design for an interconnect for electrically connecting plural electrically conductive neutral bars in fixed spaced-apart relationship, as shown and described.

DESCRIPTION

FIG. 1 is a perspective view of the front, right side, and top of an interconnect for electrically connecting plural electrically conductive neutral bars in fixed spaced-apart relationship incorporating my new design;

FIG. 2 is a front elevational view thereof;

FIG. 3 is a right-side elevational view thereof, with the left-side elevational view being a mirror image thereof;

FIG. 4 is a rear elevational view thereof;

FIG. 5 is a top plan view thereof; and,

FIG. 6 is a bottom plan view thereof.
